US0D1064829S

(12) **United States Design Patent** (10) Patent No.: **US D1,064,829 S**
(45) Date of Patent: ** Mar. 4, 2025

(54) **BOTTLE FOR COSMETICS**

(71) Applicant: **SIROK Inc.**, Shibuya-ku (JP)

(72) Inventors: **Minami Inoue**, Tokyo (JP); **Ryota Yokozeki**, Tokyo (JP); **Yuri Takayama**, Tokyo (JP)

(73) Assignee: **SIROK, Inc.**, Tokyo (JP)

(**) Term: **15 Years**

(21) Appl. No.: **35/519,336**

(22) Filed: **Jun. 26, 2023**

(80) **Hague Agreement Data**

Int. Filing Date: **Jun. 26, 2023**

Int. Reg. No.: **DM/230085**

Int. Reg. Date: **Jun. 26, 2023**

Int. Reg. Pub. Date: **Dec. 15, 2023**

(51) **LOC (15) Cl.** **09-01**

(52) **U.S. Cl.**

USPC **D9/529**; D28/76

(58) **Field of Classification Search**

USPC D9/516, 519, 529, 549, 562, 572, 573, D9/574, 575, 682, 684, 685, 686, 688, D9/689, 690, 691, 693, 694, 567; D28/4, D28/73, 76, 91.1

CPC B65D 83/205; B65D 83/207; B65D 83/30; B65D 1/0223
